(57) CLAIM

The ornamental design for portion of cosmetic container, as shown and described.

DESCRIPTION

FIG. 1 is a perspective view of the portion of cosmetic container; and,

FIG. 2 is a top plan view of the same.

The broken lines immediately adjacent the shaded areas represent the bounds of the claim and all other broken lines are for illustrative purposes only. None of the broken lines form a part of the claimed design.

1 Claim, 2 Drawing Sheets
